C. STEENSTRUP

INCLOSED FURNACE

Filed Sept. 23, 1922

Patented Mar. 24, 1925.

1,531,039

UNITED STATES PATENT OFFICE.

CHRISTIAN STEENSTRUP, OF SCHENECTADY, NEW YORK, ASSIGNOR TO GENERAL ELECTRIC COMPANY, A CORPORATION OF NEW YORK.

INCLOSED FURNACE.

Application filed September 23, 1922. Serial No. 590,007.

To all whom it may concern:

Be it known that I, CHRISTIAN STEENSTRUP, a citizen of the United States, residing in Schenectady, in the county of Schenectady, State of New York, have invented certain new and useful Improvements in Inclosed Furnaces, of which the following is a specification.

The present invention comprises an improvement in inclosed furnaces, and particularly in electric furnaces, in which the work is surrounded by a selected gas during the operation of the furnace, and also in the method of operating the same.

15 Certain metallurgical operation, for example, the uniting of metal parts by fusion of copper or other metals, in the presence of a reducing gas, are carried out in an inclosed space in large electric furnaces which are well heat-insulated. After the operation is completed a long time, sometimes several days, has been required to cool down the furnace and its contents and hence the output of the furnace has been very seriously restricted and the cost of the product has been correspondingly increased.

A slow rate of cooling in some cases is disadvantageous in its effect upon the work. For example, when uniting metal parts by fused copper, silver, or the like, in hydrogen, it is desirable to cool the work rapidly when the union is complete, particularly from the highest temperature down to a point where further alloyage or other undesired action stops.

In accordance with my invention, greater efficiency and economy of operation of gas-filled furnaces is obtained by utilizing the same gas which is necessary to the metallurgical operation as a cooling medium. This is accomplished by establishing a circulation of said gas through the furnace and cooling means after the heat-treating process has been completed. As a result of my invention a complete operation can be carried out in a large industrial furnace in less than one-fourth of the time formerly required.

As a further consequence of my invention, an improved product can be produced, particularly when coating or uniting metal by fused copper.

In the accompanying drawing, Fig. 1 is a plan view of an apparatus embodying my invention, part of the furnace cover being

broken away to show the electric heating elements, and Fig. 2 is a vertical section of a slight modification.

Referring to the drawing, the apparatus comprises a closed metal container 1 lined with suitable refractory heat-insulating materials and containing suitable heating means, as for example, electric resistors 2. Inlet and outlet pipes 3 and 4, respectively, are provided for admitting and carrying away gas, as for example, hydrogen. During the heating operation or working period of the furnace, sufficient gas is supplied to provide a slight excess so as to produce a low pressure in the confined work-containing space or chamber. During operation with a combustible gas, such as hydrogen, some gas is permitted to burn at the outlet pipe 4 to indicate whether or not a suitable pressure exists in the apparatus. The cover 5 of the furnace which during the working period is held down by bolts or clamps is removable by elevating devices engaging with the ears 6. Valve tubes 7 containing sight glasses communicate with the furnace interior to permit observation of the furnace interior. Thermo-couples may be inserted into the furnace through tubes 8.

Connected to the furnace by conduits 9 and 10 is a cooler comprising a plurality of pipes 11 located in a casing 12. A circulation of cooling water about the pipes 11 in the casing 12 is maintained by means of the inlet and outlet pipes 13 and 14.

During the period that the work is heated to carry out desired operations, as for example, the union of metal parts in hydrogen by fusion of metal, the valves 15 and 16 in the conduits 9 and 10 are closed to prevent the circulation of the gas through the cooler. After the work of the furnace is completed the supply of current to the resistors 2 is interrupted. To lower the temperature of the furnace the valves 15 and 16 are opened and a blower or pump 17 is put into operation. The blower may be driven by any suitable means, a shaft 18 being shown for the purpose. Due to the pump, the hydrogen or other selected gas is circulated through the pipes 11 where it gives up heat to the cooling fluid. During the cooling or temperature reducing period of the furnace the supply of hydrogen thereto is maintained. When the temperature has been lowered to a desired point,

the valves 15 and 16 are closed, the furnace is opened and the work removed. It is particularly desirable to lower the temperature rapidly over a range of about 100° 5 below the fusing temperature of the brazing metal so as to stop alloying action, which, particularly in the case of some metals, would tend to cause deterioration of the union or joint. With this in view the pump 10 may be driven rapidly at the start and later on at a decreased rate if a slower cooling operation is desired.

In Fig. 1 I have shown the conduits 9 and 10 leading to and from the cooler as 15 being connected at substantially diametrically opposite points to the container, and for many kinds of work this is entirely satisfactory. There are other kinds of work, however, for which this is not the 20 most advantageous arrangement. For example, in the copper brazing of parts which are placed one over the other in the container and where the center portion of each part is more massive than its peripheral 25 portion. Where such is the case, I find it preferable to deliver the gas from the cooler to the container at some central point from which the gas flows first over the massive portion of the work and then over the 30 lighter portion. To more effectively direct the cool gas baffles of any suitable character may be employed. In Fig. 2 is shown a construction suitable for the last-mentioned class of work, 1 indicates the heat-insulated 35 container which is provided with suitable heating means as before, and 20 a brick work foundation. 21 indicates the work or parts to be brazed or otherwise treated which may for example, be turbine dia- 40 phragms or wheels which are more massive in the center than at the periphery. The parts may be supported within the container in any suitable manner. The gas from the cooler enters the container by the 45 conduit 10 and flows directly downward striking the work at the center where the mass is greatest. Where the mass is greatest at the periphery a conical deflector or baffle 22 is preferably employed to deflect 50 the gas from the center toward the periphery. In the brick work is a conduit 23 which is connected to the conduit 9 leading to the pump associated with the cooler. Above the opening of the conduit 23 is a 55 baffle plate 24 which serves to direct the gas from the center outwardly and thus prevent it from shunting more or less directly from the inlet to the outlet. By the use of the means described, the parts within 60 the container may be cooled in such manner as to avoid undue strains in the parts as they are cooled.

I particularly wish to emphasize the fact that whereas the reducing gas was formerly 65 used for one purpose only, i. e. to assist in

carrying out a metallurgical process, it is now used not only for that purpose, but also to reduce the temperature of the furnace and of the work or charge contained therein. It is also to be noted that the use of 70 said gas prevents the entrance of air to the furnace during both operations.

What I claim as new and desire to secure by Letters Patent of the United States, is:—

1. An apparatus for carrying out operations in the presence of a selected gas comprising a heating chamber, a cooling device, conduits connecting said heating chamber with said cooling device, and means for circulating said gas from said heating chamber to said cooling device and from said cooling device to said heating chamber. 75

2. An apparatus for carrying out heating operations in a gas in an enclosed space comprising a sealed receptacle, means for supplying a gas thereto, heating means therefor, conduits adapted to convey gas connected at opposite ends to said receptacle to permit the circulation of gas therethrough, and means for carrying away heat from said conduits. 80 85

3. An apparatus for carrying out thermal operations in a confined space which comprises means for surrounding the charge during the heating operation by a selected gas, means for restricting the escape of heat 90 from said gas during the heating operation, and controllable means for artificially cooling the charge through the intermediary of said gas during the cooling operation. 95

4. In an apparatus for the purpose de- 100 scribed, the combination of a container for the charge, heating means therefor, means for maintaining a supply of selected gas in the container during its working period, and means for withdrawing said gas from 105 the container after the working period is completed, cooling the same and returning it to the container to reduce its temperature and also that of the charge therein.

5. An apparatus for the purpose de- 110 scribed which comprises a container for the charge, heating means therefor, means for supplying a selected gas to the container during its working period, a cooling means which is connected to the container at suitably spaced points, and means for circulating the gas through the container and cooler after said working period is completed for the purpose of reducing the temperature of the container and of the charge therein. 115

6. An apparatus for the purpose de- 120 scribed which comprises a container for the charge, heating means therefor, means for supplying a selected gas to the container during its working period, a cooling means, conduits connecting the cooling means to the container at suitably spaced points, means for preventing the circulation of gas through the conduits during the working period of the container, and means for main- 125 130

- taining a forced circulation of said gas through the container and cooling means after said working period for the purpose of reducing the temperature of the container and of the charge therein.
7. In an apparatus of the character described the combination of a container for the charge, heating means therefor, means for supplying a selected gas to the container during its working period, a cooler which is inactive during said period, conduits connecting the cooler with the container at suitably spaced points, means for causing a circulation of said gas through the container and cooler after the working period is completed, and means for directing the flow of gas over the charge within the container during the cooling period.
8. An apparatus for reducing the temperature of a charge which has been subjected to high temperatures during the working period which comprises a closed container in which the charge is located and is surrounded by a selected gas, a means for absorbing heat from the charge through the intermediary of the gas, and conduits for circulating a cooling fluid through said means.
9. The method of cooling a heated charge in a closed heating chamber containing a selected gas which consists in circulating said gas successively through said chamber and a zone maintained at a lower temperature.
10. The method of cooling a closed heating chamber containing a selected gas which consists in withdrawing said gas from said chamber, cooling said gas, and then returning the cooled gas to said chamber.
11. The method of cooling a high temperature closed furnace which contains a charge and also a selected gas which comprises establishing communication between the furnace and a cooler, and thereafter maintaining a forced circulation of said selected gas through the cooler and over the charge.

In witness whereof, I have hereunto set my hand this 22nd day of September, 1922.

CHRISTIAN STEENSTRUP.
